Phineas Davis, Baltimore, Maryland

Letters Patent July 29, 1834

The schedule referred to in these Letters Patent and making part of the same containing a description in the words of the said Phineas Davis himself of his improvement in the mode of promoting the combustion of Anthracite coal, and other fuel in the furnaces of locomotive and steam engines. Be it known to whomsoever it may concern that I Phineas Davis of Baltimore in the State of Maryland have invented a new mode of promoting the combustion of anthracite and other fuel in the furnaces of fire places of Boilers and steam engines; and that the following is a full and exact description of my said invention.

The means by which I promote the combustion of Anthracite and other fuel is by the employment of an wheel, or it may revolve, within a frame in a manner well known to machinists and my improvement consists in the arrangement of the apparatus by which I supply the grate or escape flue, to give motion to such fan or rance. As a loco-motive engine I usually employ two fan wheels and I have found them and their appendages to answer well in practice when made of the dimensions I am about to indicate although in this particular there may be considerable variation without injury to the effect.

The wheels may be from 18 to 20 inches in diameter and from 10 to 12 inches wide. They may be placed upon the same axis and at the distance of about 18 inches from each other in the class of machinery instances the gravity to each wheel will be sufficient, but a greater number may be used, the driving motion should be wheels, rattle etc, not differ from those ordinarily employed in similar flowing machinery. The wheel is contriv'd from these strong, straight bolts, seven eight inches square, which lead from them in the direction of a tangent to the circle described by the wheels, into a light ash pit under the grate of the furnace and the air by the gravity force through the pit, with such velocity as to carry the fire to burn with great energy, so as to produce an abundant supply of steam.

from an incendiary, notwithstanding the tendency of that fuel to back and thereby to impede the ordinary draft which is employed for locomotive engines. In order to give motion to the fan wheels I place a steam wheel upon the same shaft with them generally at the centre thereof so as to be equivalent from them. This steam wheel is constructed in the same manner nearly as the wind wheel differing from them principally in its dimensions and its being acted upon and impelled by an elastic fluid (steam) which may act upon and impelle in elastic fluid air. The steam wheel has usually four wings or arms of from three to five inches in width, and it may be from 24 to 24 inches in diameter. The wheel is revolved ^{with} a stream of such dimensions as just to allow the air to revolve freely within it. A tube connected with the exhaust pipe from each side of the cylinder is directed above, tangentially, and the waste steam is then injected forcibly against the outer end of the vanes impelling them and consequently the wind wheel with great velocity. The steam wheel then enters a cage at an opening or openings in the centre of the drum made similar to those at which the air enters from the action of wind to supply the fan wheel.

As it is necessary to command the blast so as to regulate the intensity of the fire which will often be to great size the whole of the waste steam discharged upon the steam wheel shall attach a branch pipe to that article conduct the steam from the cylinder to cylinder to the steam wheel and supply a valve or valves arranged as to create one to direct the whole or any certain portion of the steam through which branch pipe, and thus obtain the desired effect in the most perfect manner. The command of this supply of steam and the diminishing centrifugal force of that which has acted upon the vanes causing him to open or close the moment of his escape at the opening surrounding the centre pipe since the parts are properly proportioned to each other so although it is necessary to diminish the size of the actual velocity of the steam as the center is approached.

The opening in the steam wheel for the escape of steam

67.

I usually make in one side only and cover this with a cap or dome and from this cap or dome a tube extends upwards to carry off the steam in such a way that no inconvenience may be experienced by its discharge. Although I intend always to use the waste steam from the cylinder or cylinder it is manifest that steam may be supplied from the boiler to act upon the steam-wheel but this procedure would not be economical and would yet be a manifest violation of my rights, I am aware that in India, what such as I have described have been used to supply a blast to the furnaces of locomotive engines. I am also aware that what have been propelled by the action of steam, upon wings or canes surrounding them. I do not therefore claim either of these singly and separately as my invention but what I claim is the combination and arrangement of the parts made as I have described, by which the waste or escape steam is made to accomplish the results within a dome for the purpose of giving the steam-wheel, wholly to feed the furnaces of steam engines. And I do hereby declare that I have herein explained and set forth the what I believe to be the best method of applying the waste steam to accomplish the proposed object but that I do not intend thereby to confine myself to this precise mode of construction and arrangement but to vary the same as I may find convenient whilst it operate upon the same principle and attain the like end by analogous means.
